Patented Sept. 25, 1917.

UNITED STATES PATENT OFFICE.

ALBERT HAYES, OF NEW YORK, N. Y., ASSIGNOR TO CARNOT DEVELOPMENT CORPORATION, A CORPORATION OF NEW YORK.

BURNER.

1,241,111.

Specification of Letters Patent. Patented Sept. 25, 1917.

Application filed February 10, 1916. Serial No. 77,498.

To all whom it may concern:

Be it known that I, ALBERT HAYES, a citizen of the United States, residing at New York, in the county of New York, State of New York, have invented certain new and useful Improvements in Burners, of which the following is a description, reference being had to the accompanying drawings, forming a part hereof.

10 My invention relates to a burner for producing heat by combustion of hydrocarbon gas by which a more complete utilization of the thermal units is effected than has heretofore been possible; in other words, by which 15 more effective heat is produced from a given quantity of gas or gaseous fuel than has been possible heretofore.

It is well known that by the use of what is commonly known as the Bunsen burner, 20 that is a burner in which gas is mixed with air before it reaches the point at which it is ignited more complete combustion and a higher heat is produced than can be produced by burning gas at the tip of an ordinary illuminating gas burner. It is also well known that in a burner of the Bunsen type the completeness of the combustion is, 25 to at least a considerable extent, dependent on the completeness of the mixture of the gas and air before it reaches the point of combustion. For the purpose of effecting the intimate mixture of gas and air, the mixture has been forced through plates or diaphragms of porous earthen ware the pores 30 being so fine as to cause the gas and air to be very finely divided and consequently very intimately mixed before reaching the surface at which combustion takes place with the result of producing at such surface or 35 close to it non-luminous or what has been termed "flameless" combustion. But this so-called "flameless" combustion being produced at or substantially at the surface of the porous plate or diaphragm does not result 40 in producing the effective heat which should be produced by the gas used, for the reason that combustion is not complete, the heat produced being disseminated by the atmosphere and getting away without it being possible to fully utilize it and carrying with it more or less unconsumed carbon.

It is the object of my invention to provide a construction of burner by which a suitable mixture of gas and air or gas and steam may be ignited at the base of a column or mass of

refractory material in pieces or fragments, so that combustion will take place at the base of the column or mass of refractory material with the effect of causing the refractory material to become incandescent from the point at which combustion takes place upward to its upper surface so that any of the mixture of gas and air which may not be burned at the point at which the primary combustion takes place will be burned as it passes through the mass of incandescent refractory material with the result that it yields in effective form all or substantially all of the thermal units which it contains.

With these and other objects hereinafter explained in view, my invention consists in the construction and combination of elements hereinafter described and claimed.

Referring to the drawings,

Figure 1 is a vertical section of a burner embodying my invention.

Fig. 2 is a horizontal section on line 2-2 of Fig. 1.

In the drawings 1 indicates a column of fragments or pieces of refractory material such as alundum, graphite, chrome ore or the like though fire brick may be used. The bottom layer 2 of this column is formed of relatively small or fine pieces of refractory material which will pack together so as to leave only very small spaces between them. Above this layer the pieces or fragments of refractory material are larger so as to leave spaces between them of such size as to readily permit flame to flash or jump back through them to the bottom layer 2. This column of fragments of refractory material is supported by a grid 3 in a tube 4 which may be of any desired cross-section. Below this grid 3 is a chamber 4 which is supplied with an explosive mixture of gas and air or gas. In the burner shown this chamber 4 is connected by tubes 5 of relatively small diameter to a lower mixing chamber 6 to which gas and air or gas and steam is admitted through pipe 7 to which gas is supplied by pipe 8, and air by pipe 9, pipe 8 being provided with controlling cock 10 and pipe 9 being provided with controlling valve 11. The gas and air are both under slight pressure only, the pressure at which gas is supplied in ordinary city gas service being sufficient, and the air pressure is only sufficient to provide a supply of oxygen sufficient for complete combustion of the gas. The gas

and air may be supplied directly to the chamber 4.

In use, the gas and air being turned on the mixture is forced upward through the 5 column and is ignited by any convenient means. The flame at once flashes or jumps back to the base of the column and burns in or below the layer 2 of relatively fine fragments heating this layer at once to incandescence and quickly bringing the entire 10 column to incandescence. Any gas which is not completely consumed in this lower layer, as it passes upward through the column 15 comes in contact with the incandescent fragments and its combustion is made complete with the result that there is no unconsumed carbon in the products of combustion and no luminous flame.

By providing the lower mixing chamber 20 6 and connecting it to the mixing chamber 4 by the tubes 5, any danger of the flame flashing or jumping back to the pipe 7 is obviated and a thorough mixing of the gas, that is the hydrocarbon carrying gas, and 25 the air, that is the oxygen carrying gas, is secured.

I do not herein claim the method of producing complete combustion carried out in the burner above described, as that forms the 30 subject matter of a separate application filed February 10, 1916, Serial No. 77,497.

Having thus described my invention what I claim is:

1. The herein described burner comprising a vertical tube closed at its lower end 35 and having a grid extending across it near its lower end, means for supplying hydrocarbon gas and oxygen carrying gas to the space below the grid, a layer of relatively fine fragments of refractory material immediately above the grid and relatively large fragments of refractory material above and resting on the layer of relatively fine fragments.

2. The herein described burner comprising a vertical tube closed at its lower end and having a grid extending across it near its lower end, a layer of relatively fine fragments of refractory material immediately 45 above the grid and relatively large fragments of refractory material above and resting on the layer of relatively fine fragments, a chamber below the bottom of the tube, tubes of relatively small diameter leading from the chamber to the space between the 50 bottom of the tube and the grid, and means for supplying hydrocarbon gas and oxygen carrying gas to said chamber.

This specification signed this 10th day of February, A. D. 1916.

ALBERT HAYES.
